UNITED STATES PATENT OFFICE.

JEAN CASTRO, OF BROOKLYN, NEW YORK, ASSIGNOR TO FRANK & COHEN SILK CORPORATION, A CORPORATION OF NEW YORK.

DESIGN FOR A TEXTILE FABRIC OR SIMILAR ARTICLE.

Application filed October 22, 1928. Serial No. 28,586. Term of patent 3½ years.

To all whom it may concern:

Be it known that I, JEAN CASTRO, a citizen of the United States, residing at Brooklyn, in the county of Kings and State of New York, have invented a new, original, and ornamental Design for a Textile Fabric or Similar Article, of which the following is a specification, reference being had to the accompanying drawing and to the accompanying sample of goods bearing the design, forming a part thereof.

The figure on the drawing is a plan view of a piece of textile fabric bearing my new de-

sign, the area defined by the indicating arrows 1, 2, 3, and 4 showing, substantially, a unit thereof. The arrow 5 in conjunction with the arrow 2 shows how the design unit is repeated; for example, the upper left corner of the unit being repeated in the lower angle formed by the arrows 2 and 5.

I claim as my invention:

The ornamental design for a textile fabric or similar article substantially as shown and described.

JEAN CASTRO.
